[57] CLAIM

The ornamental design for a crib footboard, as shown and described.

DESCRIPTION

FIG. 1 is a front view of the crib footboard of the present invention;

FIG. 2 is a side view thereof;

FIG. 3 is a top plan view thereof;

FIG. 4 is an enlarged sectional view taken along line 4—4 of FIG. 1;

FIG. 5 is an enlarged sectional view taken along line 5—5 of FIG. 1; and

FIG. 6 is an enlarged sectional view taken along line 6—6 of FIG. 1.

The rear surface is conventional in appearance with the exception of the appearances of the two legs which are mirror images of the front views thereof.

FIG. 1

FIG. 2

FIG. 3

FIG. 4
